(57) CLAIM

The ornamental design for a bench, as shown and described.

DESCRIPTION

FIG. 1 is a top perspective view of a bench, showing my new design;

FIG. 2 is a bottom perspective view thereof;

FIG. 3 is a top plan view thereof;

FIG. 4 is a bottom plan view thereof;

FIG. 5 is a left-side elevation view thereof;

FIG. 6 is a right-side elevation view thereof; and,

FIG. 7 is a front elevation view thereof, the rear elevation view is a mirror image thereof.

The broken lines shown in the drawings depict portions of the bench that form no part of the claimed design.

1 Claim, 7 Drawing Sheets
